UNITED STATES PATENT OFFICE.

STEWART WATT AND FORREST H. WATT, OF BARNESVILLE, OHIO; SAID
FORREST H. WATT ASSIGNOR TO SAID STEWART WATT.

TWYER FOR CUPOLA-FURNACES.

SPECIFICATION forming part of Letters Patent No. 697,301, dated April 8, 1902.

Application filed January 6, 1902. Serial No. 88,619. (No model.)

To all whom it may concern:

Be it known that we, STEWART WATT and FORREST H. WATT, of Barnesville, Belmont county, and State of Ohio, have invented certain new and useful Improvements in Twyers for Capola-Furnaces; and we hereby declare that the following is a full, clear, and exact description thereof, reference being had to the accompanying drawings, which form part 10 of this specification.

This invention is an improvement in twyers for cupola-furnaces; and its objects are to provide a twyer which will enable the foundryman to maintain the heat in the cupola 15 until all the melted iron is withdrawn, will enable the blast to be regulated by simply changing the fronts of the twyers, will prevent the slag capping over the bottom of the cupola and facilitate the cleaning out of the 20 cupola when its bottom is dropped, will enable the fronts of twyers to be removed and replaced at will when it is desired to alter the air-jets or clean the twyers or when necessary to replace burned-out twyers, and by 25 which the air can be distributed evenly and uniformly through the cupola and directed away from the fire-brick, so that the latter will not be destroyed by impact of jets, as frequently occurs in the ordinary cupola-furnaces, and to make the twyers applicable to 30 any ordinary construction of cupola at little expense.

The invention consists in the novel construction of the twyers, as hereinafter described and claimed, and the accompanying drawings represent forms of twyers severally embodying the invention and which we will now describe, premising the detailed description thereof with the statement that the dimensions of the twyers and their forms can be varied, as hereinafter suggested, to meet the requirements of the particular cupola to which they are to be applied or the judgment of the foundryman within the scope of the invention.

In said drawings, Figure 1 is a vertical sectional elevation of a portion of a cupola-furnace with one form of our improved twyers applied thereto. Fig. 2 is a horizontal section on line 2 2, Fig. 1. Fig. 3 is a rear view

of one of the twyer-fronts detached. Fig. 4 is a detail face view of a modified form of twyer suitable for smaller cupolas. Fig. 5 is a horizontal section therethrough on line 5 5, Fig. 4. Fig. 6 is a vertical section there- 55 through on line 6 6, Fig. 4. Fig. 7 is a view of an annular twyer, partly in section; and Fig. 8 is a detail section through a solid-bot- tom twyer.

A designates an ordinary cupola-furnace 60 having a lining B, of fire-brick, and an exterior metal sheathing a. Within this furnace, near the bottom thereof, are arranged the twyers D. These twyers are arranged in a circle within the cupola and take the place of 65 the fire-brick at this point. Each twyer D preferably is composed of a hollow casting, preferably of segmental shape and narrower (on radial lines) at bottom than at top to prevent falling metal, slag, &c., catching on the 70 face of the twyer or filling the jet-opening therein. Preferably, also, the bottom of the twyer-casting is open, but is closed by the underlying fire-brick, the bottom being prefer- 75 ably left open, so that in case refuse or slag should perchance get into the twyer it can be taken therefrom without displacing the twyer by removing the underlying fire-brick and cleaning the twyer-casting through the bot- 80 tom opening therein. In the back wall of the twyer is a blast-opening d, which communi- 85 cates directly with the annular wind-box C, surrounding the cupola, as usual. In the front or inner face of the twyer-casting D are formed a series of jet-openings d' d'', the former 90 being shown as horizontal openings, while the latter are upwardly inclined, and these open- 95 ings may be surrounded with tubular exten- sions or projections d''' within the casting and on the front thereof, said extensions project- 100 ing into the twyer-chamber and practically forming short jet-pipes, by which the air- blasts will be directed upwardly and inwardly in the most advantageous manner. The ar- rangement of jet-openings shown in Fig. 1 of 95 the drawings we have found very advanta- geous in large cupolas, and the air is thereby directed away from the superimposed fire- bricks, and the rapid destruction of the latter thereby prevented. The arrangement of the 100

air-jets in the twyer may, however, be varied to suit the foundryman and the nature of metals being melted and fuel employed.

While the front or inner faces of the twyer-castings might in some cases be made integral, we prefer to form them separately from the body portions of the casting for economical and practical reasons. First, these inner faces might be burned out or broken or clogged, and in any such event it is obvious repairs can be more quickly and economically made by removing the old fronts and replacing them with new than if the whole twyer had to be removed and replaced; second, in some heats it may be desirable to have more air jetted at top of twyer than at bottom, or vice versa, or to have air jetted inwardly at a different angle from what would be advantageously employed in other heats, and by providing suitably-constructed sets of interchangeable fronts it is obvious that the foundryman can at little expense alter his cupola to suit any particular "heat" he desires to make. Therefore we preferably make the fronts or inner plates D' of the twyers removable, but secure them to the bodies by means of bolts d^4 , tapped through the fronts and engaging lugs D³ within the twyers, as shown.

The construction shown in Figs. 1 to 3 is peculiarly well adapted for large cupola-furnaces having external wind-boxes. The twyers should in all cases be duly proportioned to the cupola for which they are intended and may be individually removed and replaced when necessary at little expense. Some cupola-furnaces (particularly the smaller ones) do not have wind-boxes, and for such cupolas the twyers are made of greater or less length or arc, according to the number of blast-pipe connections which the cupola may have. Where but one blast connection is used, the twyer may take the shape of a ring or annulus, as in Fig. 7. Where two blast connections are provided, the twyers would be semicircular in plan, the number of twyers employed and the relative length of such twyers depending upon the number of blast connections in cupolas having no wind-box. These large twyer-castings are shown in Figs. 4 to 8 and are provided with two or more similar removable front sections D', which may be detachably secured to the twyer by bolts e', as shown, and are provided with air-jet apertures d' d^2 and tubular extensions d^3 around openings d^2 , as in the case of the narrow twyers. In order to prevent the roof or upper portion of these large twyers sagging when hot, it is, however, desirable to brace them by vertical front stays E, which extend from top to bottom of the twyer and are arranged intermediate the adjacent removable fronts D', as shown. These stays may be provided with jet-apertures E', which will assist in keeping down their temperature. Where the bottom of the twyer is left open, the lower ends of the stays E and the rear walls of the twyer are connected by bottom

stay-bars E², as shown. The twyers are also slightly tapered in cross-section, so that (measured on radial lines) their bottoms are narrower than their tops for the same purpose that the smaller twyers D are made narrower at bottom than at top. All the twyers are made and fitted so closely in the cupola that the air blown thereinto must pass out through the jet-openings therein, and as these openings can be varied or regulated by properly casting the fronts the air-jets can be directed in the most advantageous manner to suit the foundryman, the interchangeable fronts being readily attachable and detachable, while the twyers remain fixed in the walls of the cupola.

In the ordinary construction of cupola-twyers the blast impinges on the fire-brick and rapidly burns out the latter, necessitating frequent and costly repairs of the brick lining, which is both expensive and troublesome; but by properly shaping the apertures in our twyer-fronts this objectionable incident can be obviated.

Where cupolas have a wind-box, the small twyers shown in Figs. 1 to 3 are preferred; but where the cupolas have no wind-box, but admit air through one or more openings in shell, the larger twyers may be used, and the number and size of such twyers will vary with the number of air-inlets in shell, as above explained.

The twyers may be formed of any suitable material, but are preferably made of cast-iron. The twyers form part of the inner lining of the cupola, and therefore become very hot, and when the blast enters the twyers it becomes heated therein before it passes into the cupola through the jet-openings, the blast being sufficient to keep a supply of air under pressure in the twyers during the operation of the cupola. The warming of the air facilitates the maintenance of the desired temperature in the cupola and lessens the expenditure of fuel necessary to do this.

The blast-inlet holes in back of twyers can be made of any shape and size and location to fit the openings in shell of cupola when the invention is adapted to old cupolas without remodeling the latter. The blast-holes in fronts of twyers should be so arranged that they will equally distribute the air in the melting zone within the cupolas, which distribution facilitates the rapid and uniform melting of the metal. The tubular extensions d^3 around jet-openings d^2 cause the air to penetrate farther into the cupola before disseminating therein than where it simply passes through plain apertures in the fronts. By forming the blast-inlet openings d higher or lower on the twyers the latter can be located at any desired height above the bottom of the cupola to which they are to be attached, thus enabling the melting zone to be regulated and located at the point desired by the foundryman, and this capability of construction is particularly advantageous where it is

desired to alter old cupolas for producing heavy instead of light castings, or vice versa. Our twyers also prevent the formation of slag caps or bridges, and when the bottom of the cupola drops everything goes out and the danger and annoyance of slag formations in cupola are prevented. The blast-holes can be located at any desired point on the twyers. If it is desired to lower the melting zone only slightly, it can be done by stopping up some of the upper jet-holes with fire-clay without changing the fronts.

Having thus described our invention, what we therefore claim as new, and desire to secure by Letters Patent thereon, is—

1. In a cupola-furnace, a series of twyers adapted to form part of the lining of the cupola, each consisting of a hollow body having an air-inlet in its back and its inner or front end open, and a removable changeable face or front plate secured to and closing the inner end of each body, each plate being provided with jet-apertures, substantially as described.

2. In a cupola-furnace, the combination of a twyer consisting of a hollow casting adapted to form part of the inner lining of the furnace and having a removable changeable front piece provided with jet-apertures, an air-trunk exterior to the twyer and communicating with the rear end thereof, and an air-supply pipe, substantially as described.

3. In a cupola-furnace, the combination of a series of similar twyers each consisting of a hollow segmental casting, adapted to form part of the lining of the furnace, and having an air-blast inlet at rear but open at its front or inner end, and each twyer having a removable front piece closing its inner end provided with a series of air-jet openings; with an air-trunk exterior to the twyers, and an air-supply pipe, substantially as and for the purpose described.

4. A twyer for cupola-furnaces, having a blast-inlet at rear, jet-apertures in its front 45 and tubular projections within the twyer around such openings, substantially as described.

5. A twyer for cupola-furnaces, consisting of a hollow casting, having a blast-inlet in 50 rear, a detachable front provided with jet-apertures, and tubular projections within the twyer surrounding the jet-openings, substantially as described.

6. A twyer for cupola-furnaces comprising 55 a hollow casting wider at top than at bottom, having a blast-inlet at rear, and a removable front provided with air-jet openings some of said openings having tubular projections around their inner ends within the twyer, substantially as described.

7. A twyer for cupola-furnaces consisting of a hollow casting having an air-inlet at back, removable fronts provided with jet-apertures, and intermediate vertical stays or braces, also 65 provided with jet-apertures, substantially as described.

8. The combination with a cupola-furnace of a series of similar twyers therein each consisting of a hollow segmental casting, adapted 70 to form part of the lining of the furnace, and having an air-blast inlet at rear, and a removable front piece provided with a series of air-jet openings, and inclined tubular extensions or projections on the inner face of the front 75 around several of the jet-openings, all substantially as and for the purpose set forth.

In testimony that we claim the foregoing as our own we affix our signatures in presence of two witnesses.
